WAISTBAND LINING STRUCTURE FOR
TROUSERS

Samuel F. Stein, Milton, Pa.

Application April 7, 1949, Serial No. 87,639

2 Claims. (Cl. 2—236)

1

My invention relates to garments and in particular to men's and boys' trousers as well as ladies' slacks or skirts, and the object of my invention is to facilitate the alteration of the waist measurement of such garments, when desired, as well as facilitate the changing the fashion thereof, as will be explained in detail in this specification.

In the drawings:

Fig. 1, illustrates a portion of the front part of a man's trousers, having a continuous waist portion, showing the formation of a folded pleat;

Fig. 2, shows the pleat unfolded at the top edge of the front part and a portion of the waist lining stitched therat;

Fig. 3, illustrates the formation of a pleat extending across the waist lining as a continuation of the front part pleat shown in Fig. 1;

Fig. 4, illustrates the pleats referred to Fig. 3, (with part of the material removed) showing the pleats secured by stitches at the inner side thereof;

Fig. 5, illustrates the waist lining attached to the inside of the trousers;

Fig. 6, illustrates a modification comprising a strap adjusting device which may be employed.

Taking men's trousers, for example, there are trousers on the market that are made with plain fronts, that is, the fronts have no pleats. There are others that comprise pleated fronts, and while the latter fashion appeals to some persons the more conservative or stout person prefers the former fashion, that is, trouser fronts without pleats.

As trousers are customarily made, in the case of pleated fronts, there is a pleat or two at each of the front parts constituting the fore portion of the trousers. These pleats are suitably secured and pressed down to retain the desired folded form before any operation is performed to the top edge of the respective fronts or before the waistband is attached to the top of the trousers, which waistband extends around the top of the complementary front parts and back parts of the trousers. The waistband is equipped with a suitable lining stitched to its top edge and extends downwardly towards the inside of the trousers to an extent slightly further than the width of the waistband, where the said lining is secured by stitching around the inner side of the waist portion of the trousers.

In the event that it be required to remove the pleats it presents a very difficult task. It necessitates the ripping of the seam attaching the waistband to the top edge of the respective front parts in order to unfold the pleats; more material has

5 to be added to the length of the waistband at each front part, and in like manner the lining requires more material to correspond with the increased length of the waistband and the ripped seam is then sewed again as it was originally. The waist measurement of the garment is thus enlarged, if the enlargement is desired, but if the object of this operation is to remove the pleats and the waist measurement is to remain as it 10 was, then it necessitates reducing the waist measurement by an operation at the back seam of the trousers. It will be seen that the aforesaid procedure is quite an extensive one and it requires a great deal of skill to do the job.

15 In the drawings: 10, is one of two front parts which constitute the fore portion of a pair of trousers; 11, is a pleat formed substantially midway of the width of the upper portion of said front part; 12, is the waistband lining; 13, illustrates the stitches that attach the said lining at the top edge of said front part. The lining carries with it a strip of canvas or stiffening 14. The stitches 13, are produced preferably, by a zig-zag special sewing machine which feeds the 20 lining off a continuous roll and by means of a folder device, the lining 12, is neatly attached at the trouser top with the upper edge of the lining 12, folded in; 15, is a fold across the lining strip which also includes the canvas strip 14; 16, is a line of stitching for keeping pleat 11, and fold 15, in position, closing the fold 15 through its 25 entire length, but pleat 11, is closed only a short distance from the top of the front part, when the pleat extends down as an open fold a suitable distance until the pleat disappears and takes the 30 form of a mere crease 17.

35 It is preferred that the stitching 16, does not comprise a short or tight stitch to facilitate ripping this line of stitching, in order to make the desired alterations described herein. Instead of the inside stitching 16, outside stitching may be used to close part of pleat 11, and fold 15; a line of stitching 18, preferably produced by a blind-stitch machine is used for attaching the waistband lining to the inside of the trousers; 19, is a portion of the trousers side pocket material to 40 which the lower edge of the lining is attached.

45 An adjusting strap 20, in conjunction with buckle 21, or some other fastening device, may be employed whereby the ripping would be obviated 50 in case of alteration, as the strap and buckle would be used for holding the pleat 11, in position and stitching 18 would hold fold 15, in place. However, a line of stitching 16, may be used in conjunction with the strap and buckle adjusting 55 means if desired.

Referring further to the drawing: 22, represents an inwardly projecting fold of fore part 10; 23, represents an outwardly projecting fold of fore part 10; 24, represents an inwardly projecting fold of waistband 12; 15, (as previously referred to in the specification) represents an outwardly projecting fold of waistband 12; 26, represents the impression on the fore part material by fold 23 when the pleat was initially pressed.

My invention contemplates the formation of the front parts 10 of the trousers with a continuous waist portion, thereby eliminating thereat superfluous thickness caused by the seam that would be required for attaching a separate waistband to the upper portion of the front parts of trousers. The continuous waist construction renders feasible the extension of pleats 11, to the extreme edge of the top of the front part 10, and when the pleats 11, are formed they are left free and unattached near the top edge of the front part 10, so that the folded pleat 11, may be conveniently unfolded to permit the waistband lining 12 to be attached to the top edge of the front part 10, by stitches 13, in the same manner as if there were no folds or pleats thereat, and when the lining 12, is attached, the pleats 11, which were temporarily unfolded for the stitching operation regain their pleated form. The band lining 12, is then folded in a similar way as a continuous fold, of the front pleat 11, and the lining 12, is then turned downwardly toward the inside of the trousers after having been folded near the line of stitching 13. The lower edge of the lining 12, is then secured to the inside of the trousers, securing simultaneously fold 15, thereat by stitching 18.

As stated before, the lining 12 carries with it a strip of stiffening material 14, and when the fold 15 is formed across the lining 12 the stiffening material 14 is included in the fold. This presents a very desirable feature in the construction of the waist portion of the trousers, that the fold 15 is stiffened by the several thicknesses of lining and stiffening material thereat, causing the waist lining to be rigid and maintain its upright position, thus preventing the top portion of the lining from bending outwardly over the top edge of the wearer's belt when a belt is through dropped loops, or when no belt is worn at all, in which case the exposure of the lining would present a very unsightly appearance at the wearer's waist, whereas my construction as described herein obviates this difficulty to a desirable extent.

While I have described the fore portion of the trousers as having a continuous waist portion, the back portion may have a separate waistband attached to the respective back parts which constitute the back portion of the trousers, if desired.

While I have shown and described a preferred embodiment of my invention, it is understood that the same is susceptible of modification in various forms without departing from the spirit and scope of my invention. I desire that what I claim be given broad interpretation and be limited only by the prior art pertaining thereto.

I claim:

1. In the production of pleated-front trousers, the method which comprises: producing a fore-part blank comprising the waist portion of the trousers, forming in said fore-part an outwardly projecting fold-line extending longitudinally to the top of said fore-part, stitching a waistband lining to the top of said fore-part and over said fold-line while the latter is temporarily unfolded at the line of stitching, forming across the width of the waistband lining an outwardly projecting fold-line which coincides with the fold-line of said fore-part and proceeds in a direct continuity of the latter fold-line, folding the waistband lining downwardly towards the inner side of said fore-part and securing the waistband lining thereat.
2. In the structure of the waist-portion of pleated-front trousers, a fore-part having a raised fold-line and a depressed fold-line spaced from the former fold-line, said fold-lines extending longitudinally to the top of said fore-part and forming a vertical pleat thereat, a waistband lining attached to the top edge of said fore-part, said waistband lining in its open extended position having a raised fold-line extending across the width thereof, which fold-line coincides with the raised fold-line of said fore-part and proceeds in a direct continuity thereof, and a depressed fold-line extending across the width of the waistband lining which fold-line coincides with the depressed fold-line of said fore-part and proceeds in a direct continuity thereof, thus forming a continuous vertical pleat that overlaps and crosses the line of attachment of the waistband lining at the top of the fore-part and extends to the end edge of the waistband lining, the waistband lining being folded downwardly substantially at the line of attachment towards the inner side of the fore-part where it is secured.
